Ade Bonneville

UNITED STATES PATENT OFFICE.

HENRY J. WARREN, OF BAYONNE, NEW JERSEY.

METHOD OF CONSTRUCTING AND CONNECTING ARTIFICIAL TEETH.

1,295,244.

Specification of Letters Patent.

Patented Feb. 25, 1919.

Application filed August 11, 1916. Serial No. 114,337.

To all whom it may concern:

- Be it known that I, HENRY J. WARREN, a citizen of the United States, and a resident of Bayonne, in the county of Hudson and State of New Jersey, have invented certain new and useful Improvements in Methods of Constructing and Connecting Artificial Teeth, of which the following is a specification.
10. This invention relates to the method of constructing and connecting an artificial tooth.
- In the accompanying drawings Figure 1 represents a side elevation of the crown, tooth and its root, with a section through the gum in which the crown is held; Fig. 2 shows a front view of the elements of Fig. 1; Fig. 3 is a section as on the line 3-3 of Fig. 2, and Fig. 4 represents a side view of an artificial tooth.
15. In the gum 20 is represented the tooth root 21 with its canal 22. The root is cut off at the gum line 23 and covered with the capping 28, having the peripheral flange 29. A hole 30 is drilled in the capping coaxial with the canal 22 of the root. A pin 32 extends through the hole 30 into the canal 22. The pin 32 loosely enters the hole 30 and said canal 22.
20. A backing is shown with the legs 35 and 36, the latter having formed therein the opening 37. The backing is located with its opening loosely engaging the pin 32 and the outer end of the leg 36 is brought to bear against the front portion of the lower face of the capping 28, so that a clearance space 38 is formed between the rear portion of the leg 36 and the rear portion of the capping 28. The facing or tooth proper 39, which is generally made of porcelain, is represented with the flat top face 40, flat rear face 41, the crowned front 42 and the opening 43.
25. The facing is placed on the backing with its top face 40 bearing against the lower face 45 of the leg 36 and its rear face 41 bearing against the inner face of the leg 35. The opening 43 of the facing is loosely engaged by the lower end of the pin 32. The leg 36 extends over the whole area of the top face 40 of the tooth 39, and the leg 35 extends over the whole area of the rear face 41 of said tooth.
30. The backing having the legs 35 and 36 with the tooth 39 are now adjusted in proper position. Wax is applied between the cap-
- ping 28 and the leg 36 of the backing as indicated at 45, to temporarily hold the capping 28, backing and pin 32 together.
- The capping 28, the backing and pin 32 while held together by the wax 45 are carefully removed from the root 21. The tooth 39 is next removed from the backing.
35. The capping, backing and pin are invested on the front and sides, the wax 45 is melted or washed out with hot water and the space between the capping and backing filled with metal like gold by means of a blow pipe for the full length of the backing as indicated at 48. After the parts are cooled the investment is removed. The capping and backing, 40 which together I call the crown, are then pickled, ground and finished. The capping is now fitted on the root to prove the fit, then taken off and the root and canal are washed with pure alcohol. The tooth 39 is next cemented on the leg 35 of the backing, and at the same time the pin 32 is cemented into the opening of the said tooth 39 and canal 32.
45. Having described my invention what I desire to secure by Letters Patent and claim is:
- The method of connecting an artificial tooth consisting in cutting a root to the gum line, fitting a capping on the root, drilling a hole in the capping coaxial with the canal of the root, inserting a pin through the capping into the root and fitting loosely therein, locating a backing against the capping with an opening in the backing engaging said pin, locating a tooth on the backing with the pin projecting into a hole of the tooth, adjusting the tooth and backing to its proper angle, applying wax to all the elements, withdrawing all elements from the root, sliding the tooth from backing, investing the parts, washing out the wax, soldering the parts 50 with metal, removing the investment when cooled, pickling, grinding and finishing the metallic elements, inserting the crown to root as proof of fit, taking off the crown, washing the root and canal thereof with pure alcohol, drying the elements, cementing the tooth on backing and cementing the pin in place.

Signed at Bayonne, in the county of Hudson and State of New Jersey, this 21st day of July, A. D. 1916.

HENRY J. WARREN.
